HOLOGRAPHIC LASER HOUSING

Eduard Gregor, Pacific Palisades, Calif., assignor to
Union Carbide Corporation, New York, N.Y.

Filed Sept. 5, 1972, Ser. No. 286,759

Term of patent 14 years

Int. Cl. D14—99

U.S. Cl. D26—14 L

FIG.1

FIG.2

FIG.3

FIG.4

FIG.5

FIG.6

FIG. 1 is a perspective view of a holographic laser housing showing my new design;

FIG. 2 is an opposite side elevational view thereof;

FIG. 3 is a top plan view thereof;

FIG. 4 is a bottom plan view thereof;

FIG. 5 is a front elevational view thereof; and

FIG. 6 is a rear elevational view thereof.

I claim:

The ornamental design for a holographic laser housing, substantially as shown.
